TRACKING DEVICE FOR AUTOMATIC MUSICAL INSTRUMENTS.

1,243,620.

Specification of Letters Patent.

Patented Oct. 16, 1917.

Application filed August 1, 1916. Serial No. 112,493.

To all whom it may concern:

Be it known that I, DOMENICO MORANO, a subject of the King of Italy, and residing in the borough of Manhattan of the city of New York, county of New York, in the State of New York, have invented certain new and useful Improvements in Tracking Devices for Automatic Musical Instruments, of which the following is a specification, reference being had to the accompanying drawing, forming a part hereof.

This invention relates to tracking devices for traveling webs and is concerned particularly with the application of such devices to the perforated note sheets of automatic musical instruments. In known automatic trackers, whether pneumatic or mechanical, lateral deviation is depended upon for initiation of the movement of the tracking members. Accordingly, such tracking devices where designed for application to sheets of a given width cannot be used with sheets of a greater width without rearrangement of the parts. By the present invention it is sought to provide improved means for insuring automatically the certain tracking of a traveling web wherein initiation of the operation of the tracking members is not dependent upon lateral deflection of the sheet but upon the frictional drag exerted thereby on a controlling member in the direction of movement of the sheet. The operation is in no wise dependent upon the condition of the edges of the sheet nor upon lateral deviation. The invention has been illustrated herein as associated with pneumatic devices for bringing about the desired registration, which pneumatic devices have their primary valves controlled by a member which is actuated mechanically under the frictional drag exerted by the sheet thereon in the direction of movement of the sheet. However, since it is believed that it is new to initiate operation of automatic tracking devices by frictional drag exerted by the traveling sheet in the direction of its movement, this application is intended to cover with breadth all devices so operated whether they be purely mechanical in character, or pneumatic or electrical. It lies within the skill of one familiar with these devices to substitute for the actuating element herein disclosed, other suitable actuating means and still retain the improved

principle of operation which constitutes the gist of the invention. Reference is now to be had to the accompanying drawings for a detailed description of the illustrated embodiment of the invention in which—

60

Figure 1 is a view in elevation of so much of a tracker-box and music sheet as is necessary for an understanding of the application of the improved tracker thereto.

Fig. 2 is a fragmentary view in side elevation of the elements shown in Fig. 1, parts being broken away in the interest of clearness. Fig. 3 is a detail view looking at the rear side of the controlling lever for the primaries of the actuating pneumatics.

70

Fig. 4 is a fragmentary detail view in plan of the controlling lever shown in Fig. 3.

In Figs. 1 and 2 there are illustrated, somewhat conventionally, the usual elements of an automatic musical instrument, including the tracker-box *a*, the music roll *b*, the wind-on roll *c*, and the tracker-bar *d*, all of which may be disposed in the usual relationship to each other. Rotation of the wind-on roll *c* may be effected through any suitable driving mechanism associated with the sprocket *c* mounted on the projecting end of the shaft of the spool. In describing the improved tracking devices it has been elected to illustrate the wind-on roll as being shiftable axially for the purpose of restoring the traveling sheet to its intended path, but, as is well recognized in the art of tracking devices, it is equally within the scope of this invention to mount this roll fixedly in the tracker-box *a* and make provision for the shifting of the tracker-bar *d* for restoration of the desired registration between the perforations *e* in the note-sheet *e'* and the usual ducts *d'* in the tracker-bar.

75

In this embodiment there is mounted directly on the tracker-bar *d*, at the rear of the music sheet *e'*, a pivoted bar or lever *f*, the forward edge of which may be beveled, as at *f'*, to bear uniformly against the reverse face of the sheet. The controlling bar is pivoted adjacent its mid point on anti-friction bearings, such as pointed set screws *g*, the ends of which take into a bearing section *f''* formed with the bar. By this construction the bar is free to rock about the bearing screws *g* in a manner which will appear. Formed on the support *h* for the

- controlling bar and disposed at opposite sides of the bearing screws g therefor, are two ports i connected with air tubes i' and having their open ends disposed directly under and near to the flat face of the controlling bar f . For the control of the open end of these ports the bar f may be formed, if necessary, with suitable lugs f^3 disposed, respectively, directly above these ports.
- 5 The tubes i' may be connected with suitable valve chambers, indicated conventionally at k , in which may be disposed secondaries of the usual type and which may communicate further through air channels formed in a
- 10 suitable block l with the interior of two actuating motor bellows m, n . The valve chamber k is connected, as usual, with the main wind-pipe o by which suction may be applied to the interior of the bellows m, n ,
- 15 according to the position of their secondaries for the purpose of collapsing one or the other of these bellows.
- Movement of the bellows m, n , may be communicated to the shiftable wind-on roll
- 20 c through any suitable mechanical connections so organized that the movement of the roll shall always serve to restore the traveling sheet to its normal path. Such mechanical connections in the preferred form in-
- 25 elude an oscillating cam member p mounted rotatably on a short shaft p' , which may be secured to one side of the tracker-box a , and this oscillating cam has formed on its curved face a cam groove p^2 , in which rests, pref-
- 30 erably with an antifriction engagement, a finger p^3 formed on the end of a longitudinally extending rod p^4 , the other end of which is engaged with the shiftable wind-on roll c through an arm p^5 . The cam mem-
- 35 ber p is secured operatively at opposite sides of its axis p' with the motor bellows m, n , through suitable rods m', n' , the connection of which with the cam may be ad-
- 40 justable through set screws g carried in col-
- 45 lars g' through which the ends of the rods pass. Normally, the connection between the rods m', n' , and the cam member p is ad-
- 50 justed so that the finger p^3 rests adjacent the mid section of the cam-groove p^2 and the
- 55 motor bellows m, n , are partially, and pref-
- 60 erably equally, expanded. At this time, the beveled edge f' of the controlling bar f bears uniformly against the rear surface of the note sheet e' and is maintained in a
- 65 truly horizontal position by the engagement of the note sheet therewith. When so positioned, as indicated in Fig. 3, the ends of the air-ports i are opened and atmospheric pressure is admitted to each of the tubes i' .
- 70 The result of this is that the interiors of the motor bellows m, n , are placed in communica-
- 75 tion with the main windway o so that these bellows tend to collapse. By reason of their opposed connections with the cam p at
- 80 opposite sides of the axis p' , however, these

bellows balance each other and cannot collapse. Likewise, they maintain the cam p in its mid position. If now, during travel of the music sheet e' , it wanders, the frictional drag thereof on the controlling bar f 70 is exerted in the direction of movement of the sheet will be sufficient to rock the bar about its pivotal support and bring the bar to bear against the end of one of the ports i , thereby closing the port without, however, changing the condition of the other port. Such change in position of the controlling bar f is indicated by dotted lines in Fig. 3. The port i so closed cuts off atmospheric pressure to its secondary, so that its motor bellows, say the bellows n , has its interior cut off from communication with the windway o while the other bellows m remains in communication therewith. The bellows m then collapses completely, while the other bellows n expands freely and the cam p is rocked about its axis p' . This rocking through the engagement of the finger p^3 with the cam groove p^2 serves to pull the rod p^4 to the left, as shown in Fig. 1, and with it shifts the wind-on roll c in the same direction. It has been found that the deflection which accompanies wandering of the traveling web is such that the web will always initiate operation of the tracking 90 members in such manner as to restore the web to its proper line of travel. After the deflection is relieved and the attendant differential frictional drag at opposite sides of the pivot eliminated the sheet returns the 95 controlling bar f to its normal, truly horizontal position. This return of its controlling bar serves to open the closed port i and restore the motor bellows m, n , to their balanced condition, in which they oppose 100 one another and hold the cam p in its mid position. The sheet is so disposed with relation to the bar that after the bar is rocked and the sheet restored to its normal path of travel, the sheet shall immediately act on 105 the bar in such manner as to overcome the difference of pressure acting in the valve seats f^3 and restore the bar to its truly horizontal position.

From the description given, it will be 115 evident that there are three conditions in the illustrated embodiment which contribute to the operation of the device in the intended manner. In the first place, in order to initiate operation of the tracking devices, there 120 must be a wandering of the sheet so that the frictional drag exerted on the bar in the direction of movement of the sheet at opposite sides of the pivot becomes unequal. The differential frictional drag at opposite sides 125 of the pivot is applied to the bar f by reason of the frictional contact of the sheet with the bar. Again, the sheet must be so disposed with relation to the bar that the differential frictional drag at opposite sides 130

of the pivot will act upon the bar to rock it about its pivot.

In order to emphasize the general applicability of the improved devices to travelling webs of any width and having edges of any character, whether torn or worn or regular, the sheet shown in Fig. 1 is indented along one edge. Since edge control is not relied on, it is immaterial to the successful operation of the improved device as to what condition the edges are in or as to how far the sheet extends to one side or the other of the controlling bar *f*.

As pointed out hereinbefore, this application is intended to cover with breadth the improved principle of actuating tracking devices, as described, and the frictional drag exerted on the controlling member in the direction of movement of the sheet may be applied with equal effectiveness to mechanical, pneumatic or electrical means for restoring the sheet to its normal path of travel. Again, this restoration may be brought about by shifting of either one of the rolls or of the tracker-bar, it being only necessary that there be relative shifting of the note sheet and the tracker-bar.

The scope of the invention will appear clearly in the appended claims.

30 What I claim is:

1. In an automatic tracker mechanism, pneumatic tracking devices having a controlling member controlled by the frictional drag of the music sheet thereon exerted in the direction of movement of the note sheet for initiating operation of said pneumatic devices.

2. In an automatic musical instrument having pneumatic tracker devices, having means engaged with the face of the note sheet and actuated by the frictional drag exerted thereon by the note sheet in the direction of movement of the note sheet to initiate operation of said tracker devices.

45 3. In an automatic musical instrument the combination with the tracker bar, of pneumatic tracking devices to maintain registration between perforations in a note sheet and the ducts in the tracker bar, and having means actuated by the frictional drag of the music sheet on said means exerted in the direction of movement of the note sheet upon wandering to initiate operation of said tracker devices.

55 4. In an automatic tracker mechanism pneumatic tracker devices, including a pivoted lever actuated by the frictional drag exerted by the music sheet thereon in the direction of the movement of the sheet upon wandering to control the operation of said pneumatic devices.

5. In an automatic tracker mechanism tracker devices, music rolls and a tracker bar, means included in the tracker devices and interposed between one of the music

rolls and the tracker bar and actuated by the frictional drag of the music sheet thereon exerted in the direction of movement of the sheet upon wandering to initiate operation of said tracker devices.

6. In an automatic tracker mechanism the combination with music rolls and a tracker bar, of a pivoted lever included in the tracker devices and disposed between one of the rolls and the tracker bar and engaged with the face of the note sheet and actuated by the frictional drag exerted thereon by the note sheet in the direction of travel of the sheet upon wandering to initiate operation of said tracker devices.

7. In an automatic tracker mechanism, tracker devices including motor bellows to maintain the sheet in its normal path of travel, valves to control the action of said bellows, and means actuated by the frictional drag exerted on said means by the music sheet in its direction of movement upon wandering to control said valves.

8. In an automatic tracker mechanism, tracker devices including motor bellows to maintain the sheet in its normal path of travel, a main windway connected operatively to said bellows and serving normally to subject the same to pressure, valves to control the action of said bellows, and means actuated by the frictional drag of the music sheet thereon exerted in the direction of movement of the sheet upon wandering to control said valves.

9. In an automatic tracker mechanism, tracker devices including motor bellows to maintain the sheet in its normal path of travel, valves to control the action of said bellows, and a pivoted lever engaged with the face of the sheet and actuated by the frictional drag of the music sheet thereon exerted in the direction of movement of the sheet to control said valves.

10. In an automatic tracker mechanism in combination with the music rolls and tracker bar, tracker devices including motor bellows to maintain the sheet in its normal path of travel, valves to control the action of said bellows, and a pivoted lever mounted between one of the rolls and the tracker bar and actuated by the frictional drag of the music sheet thereon exerted in the direction of movement of the sheet upon wandering to control said valves.

11. In an automatic musical instrument in combination with the music rolls and the tracker bar, one of the rolls and the tracker bar being relatively shiftable, tracker devices including a cam connected operatively to the shiftable member, and means actuated by the frictional drag of the music sheet on said means exerted in the direction of movement of the sheet upon wandering to initiate movement of said cam.

12. In an automatic musical instrument

- in combination with the music rolls and the tracker bar, one of the rolls and the tracker bar being relatively shiftable, tracker devices including a cam operatively connected 5 to the shiftable member, motor bellows connected with the cam to move the same and means actuated by the frictional drag of the note sheet on said means exerted in the direction of movement of the sheet to initiate 10 operation of the motor bellows.
13. In an automatic tracker mechanism in combination with the music rolls and the tracker bar, one of the rolls and the tracker bar being relatively shiftable, tracker devices 15 including an oscillating cam operatively connected to the shiftable member, motor bellows connected to the cam at opposite sides of its axis and opposed to one another, and means actuated by the frictional drag 20 of the note sheet on said means exerted in the direction of movement of the sheet to initiate the collapsing of one of the bellows while permitting the expansion of the other.
14. In an automatic tracker mechanism, 25 tracker devices including motor bellows to maintain the sheet in its normal path of travel, valves normally open to the atmosphere and connected with said bellows operatively, and means actuated by the frictional drag of the note sheet exerted in the 30 direction of movement of the sheet to close one of the valves and initiate relative movement of the bellows.
15. In an automatic tracker mechanism, 35 tracker devices including motor bellows to maintain the sheet in its normal path of

travel, a main windway connected to the bellows and subjecting the same normally to pressure, open valves controlling the connection between said bellows and the windway, and a pivoted lever actuated by the frictional drag of the sheet thereon exerted in the direction of movement of the sheet to close one of the valves and cut off its bellows from the main windway. 40

16. In an automatic musical instrument in combination with the music rolls and the tracker bar, one of the rolls and the tracker bar being relatively shiftable, motor bellows, an oscillating cam, a supporting shaft 50 therefor mounted on the tracker box, rods connecting said bellows operatively and adjustably with the cam at opposite sides of the shaft, connections between the cam and the shiftable member and means to initiate 55 operation of the bellows.

17. In combination with an automatic tracker mechanism, a tracker bar, a note sheet movable thereover, a pivoted lever included in the tracker mechanism and mounted on the tracker bar and disposed horizontally and in engagement with the flat surface of the sheet, means to maintain the perforations of the music sheet in alignment with the ducts in the tracker bar, and 60 devices controlled by said pivoted lever for initiating operation of said last named means. 65

This specification signed this 28 day of July, A. D. 1916.

DOMENICO MORANO.
